UNITED STATES PATENT OFFICE.

ALFRED DUCASBLE, OF PARIS, FRANCE, ASSIGNOR TO THE MANUFACTURED RUBBER COMPANY.

DESIGN FOR A FELLY.

SPECIFICATION forming part of Design No. 34,006, dated January 29, 1901.

Application filed January 15, 1900. Serial No. 1,563. Term of patent 14 years.

To all whom it may concern:

Be it known that I, ALFRED DUCASBLE, a citizen of the Republic of France, residing at Paris, France, have invented and produced a new and original Design for a Felly, of which the following is a specification, reference being had to the accompanying drawings, forming part hereof.

Figure 1 is a perspective and Fig. 2 a cross-sectional view of a felly having my design.

The leading feature of my design is illustrated in the drawings, and, generally speaking, it consists of a felly having straight walls, with their bases extending inward substantially at right angles to the walls and curved downward to meet the trough, the inner faces of the walls forming sharp corners at their unions with the bases.

In the drawings, *a* represents the walls, having the inwardly-sloping bases *b*, and *c* represents the sharp corners formed at the unions of the inner faces of the walls and the bases.

Having thus described my invention, what I claim as new, and desire to secure by Letters Patent, is—

The design for a felly, substantially as shown and described.

In testimony whereof I have hereunto signed my name.

ALFRED DUCASBLE.

In presence of—

R. H. BRANDON,
J. L'HERMIT.
